UNITED STATES PATENT OFFICE.

JOHN I. ASTROM, OF FORT WAYNE, INDIANA, ASSIGNOR TO FORT WAYNE ENGINEERING AND MANUFACTURING COMPANY, OF FORT WAYNE, INDIANA.

WATER-PUMPING SYSTEM.

1,412,596.

Specification of Letters Patent. Patented Apr. 11, 1922.

Application filed June 2, 1921. Serial No. 474,327.

To all whom it may concern:

Be it known that I, JOHN I. ASTROM, a citizen of the United States, and resident of Fort Wayne, in the county of Allen and 5 State of Indiana, have invented certain new and useful Improvements in Water-Pumping Systems; and I do hereby declare that the following is a full, clear, and exact description thereof.

10 This invention appertains to water pumping systems, and more particularly to a type of the same adapted for home and farm use.

The principal object of the invention is to 15 provide for a water pumping system of the class mentioned, and one wherein the parts of the same, including the storage or supply tank, are assembled into an extremely compact unit, so as to minimize the amount 20 of space required for the installation of the same.

Another object of the invention is to provide for a novel form of tank construction 25 for water pumping systems of the character set forth, and one which is capable of being installed on certain constructions of such system units, whereby to occupy the ordinarily waste space thereof.

With the foregoing and other objects in 30 view, the invention resides in the certain novel and useful construction and arrangement of parts as will be hereinafter more fully described, set forth in the appended claims, and illustrated in the accompanying 35 drawing, in which:—

Figure 1 is a side elevation of the preferred embodiment of the system unit,

Figure 2 is an enlarged vertical longitudinal section of the base of the system unit, 40 and of the tank as mounted thereon, and

Figure 3 is an inner side elevation of one of the end plates or castings of the system unit base, showing the bed plate 10 mounted thereon.

45 Figure 4 is a detail view showing another manner of mounting the bed plate upon the bracket.

Referring to the drawing, the numeral 10 designates the base or bed plate of the pumping apparatus per se, 11 the pumping mechanism having its supporting base 12 suit-

ably bolted on and at one end of the base or bed plate 10; 13 an electric motor having its supporting base suitably bolted on the base or bed plate 10, at the end thereof 55 opposite to that on which the pumping mechanism is secured, and operably connecting the latter; and 14 a casing enclosing an automatic electric pressure controller adapted to effect a starting up of the motor 13 and 60 the pumping mechanism, when the pressure of the system forces below twenty pounds, and a stopping of the same when the pressure of the system reaches forty pounds; all of a usual and known construction and 65 arrangement.

In the accomplishment of the objects and purposes of the present invention, a pair of supporting standards or members 15 and 16, preferably in the form of heavy metal 70 castings of substantially rectangular form, are provided and arranged in spaced relation, one with respect to the other, to have secured on their top edges the opposite ends of the base or bed plate 10 of the pumping 75 apparatus hereinbefore described. Both of the standards or supports 15 and 16 have their lower edge faces formed with inwardly extending flange portions 15' and 16', respectively, to provide broad substantial supporting surfaces, whereby the system unit, 80 as a whole, is practically rigid and free from undue vibration at all times, such as is necessary for the successful and efficient operation of the apparatus. 85

Formed centrally of the opposed inner faces of the standards or supports 15 and 16 are complementary circular portions 17 and 18, respectively, each outwardly concaved, and having their peripheral edges provided 90 with offset annular flanges 19 and 20, whereby to form annular shoulders 21 and 22, respectively, for the seating on the same, and the clamping therebetween of the opposite end of a tubular metal cylinder or 95 tank body 23.

For effecting the clamping of the tank body 23 in position, as stated, the circular portion 18, of the standard or support 16, is formed to provide a cylindrical boss 24, extending inwardly and concentrically of the concaved face thereof, having a threaded in- 100

wardly opening bore 25 therein for the reception of the threaded end of a tie rod or bar 26, extending centrally through the tank body 23. The standard or support 15 is formed to provide an inwardly extending flanged opening 27, disposed concentrically of its concaved inner face portion 17, and adapted to have projected outwardly therethrough the complementary end of the tie rod or bar 26, the free end portion of which is threaded for engagement in the complementary threaded bore or socket of a plug closure 28 adapted to be snugly fitted inwardly of the flanged opening 27. The outer end of the plug closure 28 is formed to provide an enlarged head portion 29 adapted to firmly bear against the outer end of the flanged opening 27, and which is preferably polygonal in form to provide oppositely disposed flat side faces for the application thereto of a tool or wrench whereby the same may be manipulated to and from position on the complementary end of the rod or bar 26. By tightening up on the plug closure 28, the opposite ends of the tank body 23 are firmly clamped in position against the opposed walls of the shoulders 21 and 22, and to an extent as to provide substantially water-proof joints therebetween. The closure plug 28 is designed to fit the bore of the flanged opening 27 in a manner also designed to prevent the escape of water or pressure outwardly thereof. In either case, however, a suitable packing (not shown) may be provided to additionally assure against any and all possible leakage of pressure or water from the completed tank.

The standard 18 is provided with an outwardly extending boss 30 having a threaded bore opening into the lower side of the tank body and is adapted to have connected thereto the water inlet pipe 31 leading from the pumping mechanism, while the standard or support 17 is similarly provided with an outwardly extending boss 32 having a threaded bore leading from the tank body and connecting a water distributing or discharge pipe connection 33.

Opening inwardly of the front side edges of the standard or supporting end plate 16 and communicating with the upper part of the tank body is a threaded opening 34 adapted to have connected thereto a pipe connection 35 leading to a pressure gauge 36, while opening into the same and communicating with the lower part of the tank is threaded opening 37 adapted to have connected thereto a drain pipe connection or valved cock (not shown) for the drawing off of all water from the tank, or from the system as a whole.

It is to be noted that each of the standards or end supporting plates 15 and 16 may have their top supporting edges each formed with a pair of spaced lugs or studs 38 adapt-

ed to engage in complementary formed recesses formed in the under faces of the opposite end edge portions of the base or bed plate 10 of the pumping apparatus, whereby to add to the rigidity of the connection between the same and the latter.

Furthermore, if desired, that portion of the bed plate 10 which rests upon the brackets may be placed between the upstanding lugs 38 as disclosed in dotted lines 75 in Fig. 3. In this, it will be noted that the bed plate 10 is bolted to the bracket element by means of a bolt 39, the same extending vertically through a flange formed on the bed plate. The head of the bolt passes 80 through a block 40 arranged with a vertically arranged slot formed in the central portion of the bracket web, the block being held down by inwardly projecting fingers 41.

Referring to Figure 4, it will be noted that the manner of securing the bed plate 10 on the bracket is similar to that above described, with the exception that the bed plate 10 extends the full width of the 90 bracket and its flange is provided with recesses to receive the lugs as described hereinbefore.

It is well understood that, while the apparatus has been described and illustrated 95 in a preferred embodiment, and in specific terms and details of construction, arrangement and assembly of parts, various changes in and modifications of the same may be resorted to without departing from the spirit 100 of the invention, or scope of the claims appended hereto.

Having thus fully described the invention, what is claimed, is:—

1. A water pumping apparatus including 105 a base plate, end plates supporting said base plate, an open ended tank extending between said end plates and having its ends closed thereby, and means for clamping said tank and end plates together.

2. The combination with a water pumping apparatus including the base or bed plate thereof, of end plates supporting the opposite ends of the said base or bed plate, an open ended tank body extending between 115 said end plates and having its open ends closed thereby, and means for clamping said tank body and said end plates together.

3. The combination with a water pumping apparatus, including the base or bed 120 plate thereof, of end plates forming standards for the supporting of the opposite ends of the said base or bed plate, an open ended tubular tank body extending between said end plates and having its open ends 125 closed thereby, and means connecting said end plates for clamping the same and said tank body together.

4. The combination with a water pumping apparatus including the base or bed 130

plate thereof, of oppositely and outwardly concaved end plates forming standards for the supporting of the opposite ends of said base or bed plate, an open ended tubular tank body extending between said end plates and having its open ends closed thereby, and a tie rod extending centrally through said

tank body and removably connecting said end plates for clamping the same and said tank body together.

10

In testimony that I claim the foregoing I have hereunto set my hand at Fort Wayne, in the county of Allen and State of Indiana.

JOHN I. ASTROM.
